UNITED STATES PATENT OFFICE

SAMUEL GOLDHEIR, OF BROOKLYN, NEW YORK

COMB-VENDING MACHINE

Application filed October 11, 1927. Serial No. 225,424.

This invention relates to a comb vending machine adapted for the purpose of selling combs when a coin is inserted in the coin slot of the said vending machine.

5 The object of the invention is to provide a comb vending machine of simple construction and arrangement of parts, embodying certain novel features hereinafter more fully described, claimed and illustrated in the accompanying drawing.

10 Fig. 1 is a perspective view of my improved comb vending machine.

Fig. 2 is a vertical longitudinal sectional view thereof.

15 Fig. 3 is a horizontal sectional view taken on the line 3—3 of Fig. 2.

Fig. 4 is a fragmentary sectional view thereof showing the coin lever in a downward or engaged position.

20 Fig. 5 is a perspective view of the comb and cover sold in the machine.

As here embodied my improved comb vending machine comprises a case 10 of box-like construction provided with an open side 25 adapted to receive the removable cover 11, hinged as at 13 and may be locked as at 12.

The case 10 is provided with an intermediate wall 14, having an angularly displaced lower portion 15 intercommunicative with the 30 opening 16, formed in the lower front portion of the case 10.

The retaining plate 17 is slidably mounted in the rear portion of the case 10 and has attached thereto a tension spring 18 also attached to the intermediate wall 15.

35 The above described construction is such as will normally permit the retaining plate 17 to close the lower portion of a compartment 19 adapted to receive a plurality of 40 combs 20 placed in covers 20' and boxes 20" which are placed in a vertical pile, one on top of each other and forced downwardly by a weight 20'.

45 The engaging lever 21 is slidably mounted in the wall 14, and is provided with extended elements 22 somewhat formed upwardly therefrom, and is provided with second extended elements 24 formed somewhat below the said extended elements 22. The coin lever 50 26 is pivotally attached to the engaging lever

21, as at 27 and is provided with an enlarged free extremity 28 formed so as to provide a recess or partial opening adapted to receive a coin. The tension spring 29 is attached to the coin lever 26 and to the gauging member 30 so as to normally hold the coin lever in an angularly inclined upward position.

55 The gauging members 30 and 31 are adjustably attached to the brackets 32, 33 and 34, 35, respectively, by means of the screws 36, 60 mounted in the said brackets and engaging in elongated apertures 30' formed in the said engaging members.

65 The bracket 35 is provided with an extended portion 37 adjacent to one side of the coin lever 26. The plate member 38 is secured to the bracket 39, attached to the cover 11 and is adjacent to the opposite side of the coin lever 26 to form a closure on this side. The extended portion 37 of the bracket 35 is 70 formed with a projection 40 for the purpose as hereinafter set forth. The plunger 41 is slidably mounted in the front portion of the case 10, held against rotation by pin 23 engaging in groove 41' and is normally held in 75 an outwardly extended position by means of the expansion spring 42, wound thereon. The plunger 41 is provided with an enlarged head 43 or handle and is also provided with an enlarged inner extremity 44 having formed therein a concave cam shaped recess 45, adapted to receive the free extremity of the coin lever 26, when the coin lever descends to a horizontal position due to the weight of a coin dropped thereon. The extremity 44 may 80 be angularly set as desired by the set screw 44'.

85 It will be understood that the gauging members 30 and 31 are positioned directly below the opening 46 formed in the top of the 90 said case, and that the said gauging members may be relatively positioned or spaced, as is required to permit a coin, such as is required to purchase a comb to slidably pass or fall intermediate the said gauging members.

95 It is obvious from the foregoing description that a coin when inserted in the opening 46 will strike the free extremity of the coin lever 26, forcing same downwardly in a horizontal position. A stop 21' projecting from 100

the lever 21 limits the downward motion of the coin lever to a horizontal position. The plunger 41 is then pressed or pushed inwardly, and engages the free extremity of the coin lever 26, causing the engaging lever 21 to engage or strike the retaining member 17 which is forced from under the combs 20 into the space 47, provided by means of the cap 48 secured to the rear portion of the case 10. It will 10 also be understood that the extended elements 22 of the engaging member 21 slidably engage between the lower comb 20^b in the above mentioned pile, and the upper adjacent comb as a means of permitting only one comb to be released. As the coin lever 26 moves inward due to the manual pressing inward of the plunger 41, the coin in the extremity 28 is pushed off by abutting projection 40 and falls to the bottom of the box. The recess 45 holds 20 the coin arm in horizontal position until plunger 41 is allowed to move outwards, and at the very first chance spring 29 lifts the coin lever 26 to its tilted normal position. The angular position of cam shaped recess 45 determines the position at which the spring may lift the coin lever, and allows an adjustment so that dishonest persons may not depress the plunger after it is partially out and get additional combs.

30 I have also provided a lever 49 pivoted intermediately, as at 50, to the side of the case 10, and having a curved portion 51, the extremity 52, engaging or in contact with the said lower comb in the said pile. The lever 49 is provided with an enlarged free extremity 53, having affixed thereto the word "empty" or any suitable similar wording. The latter described construction is such as will permit the lever 49 to pivot or swing downwardly, as 35 designated by the reference numeral 54, when the supply of the said combs has become exhausted, so as to permit the word "empty" to be visible through the transparent member 55 suitably secured to the front portion of the 40 case 10, as a means of notifying prospective purchasers that the said case 10 is empty.

Having thus described my invention, what I claim as new and desire to protect by Letters Patent of the United States is as follows:

50 1. A comb vending machine, comprising a casing with a coin receiving opening and a comb discharge opening, and arranged for holding combs, a coin lever arranged for moving into horizontal position upon receiving 5 a coin thru the said coin opening, a plunger for moving the coin lever in a horizontal direction for dispensing one comb thru the discharge opening, a projection for pushing the coin off the coin lever during the dispensing 10 operation of the latter, a spring for urging the coin lever into raised position, and the end of the plunger being formed with a cam recess for receiving the end of the coin lever so as to allow the said spring to raise the coin 15 lever upon backward motion of the plunger.

2. In a comb vending machine of the class described, a coin lever arranged for moving into horizontal position upon receiving a coin, a plunger for moving the coin lever in a horizontal direction for dispensing one comb, a projection for throwing the coin off of the coin lever upon motion of the latter, a spring for urging the coin lever into raised position, and the end of the plunger being formed with a cam recess for receiving the end of the coin lever so as to allow the said spring to raise the coin lever upon backward motion of the plunger.

3. In a comb vending machine of the class described, a coin lever arranged for moving into horizontal position upon receiving a coin, a plunger for moving the coin lever in a horizontal direction for dispensing one comb, a projection for throwing the coin off of the coin lever upon motion of the latter, a means for urging the coin lever into raised position, and the end of the plunger being formed with a cam recess for receiving the end of the coin lever so as to allow the said means to raise the coin lever upon backward motion of the plunger.

In testimony whereof I have affixed my signature.

SAMUEL GOLDHEIR.
